SKI HARNESS

David A. Wallace, Detroit, Mich.

Application May 14, 1942, Serial No. 442,889

6 Claims. (Cl. 280—11.35)

This invention relates to an improved ski harness.

More particularly the invention relates to the provision in a ski harness of improved toe clamping mechanism.

One of the main objects of the invention is the provision of improved toe clamping mechanism which is adapted to release the toe of a ski shoe when the latter is twisted to a predetermined angle with respect to the length of the ski to which it is attached in order to guard against excessive twisting of the skier's leg and consequent injury.

A further object of the invention is the provision in ski harness toe clamping mechanism of means for adjustably predetermining the angle of movement of a ski shoe with respect to the ski at which releasing of the shoe occurs.

A further object of the invention is to provide means for yieldably clamping the toe of a shoe to a ski which is adjustable in tension without varying the angle at which release of the toe clamping action takes place.

A still further object of the invention is the provision of means for independently predetermining the position of opposed jaws of toe clamping mechanism of this character by individual adjustment of the resilient members by which they are urged together.

An additional object of the invention is to provide means in ski harness toe clamping mechanism by which can be independently predetermining the angles on respectively opposite sides of the longitudinal axis of a ski at which releasing of the shoe will take place in order that the shoe may, if desired, be automatically freed from the ski when turned to a different angle in one direction with respect to the ski than in an opposite direction.

Another object of the invention is the provision of a heel holding spring in a ski harness of this kind which serves to urge the shoe into clamping engagement with the toe clamp during normal operation and which also functions to automatically eject the shoe from the harness when the toe of the shoe is released from the toe clamp by twisting of the shoe relative to the ski in the plane of the latter.

Illustrative embodiments of the invention are shown in the accompanying drawings, in which:

Fig. 1 is a side elevational view of a ski harness embodying the invention showing a ski shoe in place thereon.

Fig. 2 is a plan view of the ski harness illustrated in Fig. 1, the shoe being removed.

Fig. 3 is a transverse vertical sectional view taken on line 3—3 of Fig. 1.

Fig. 4 is a view similar to Fig. 2 showing in plan view a ski harness embodying a modified form of the invention.

Fig. 5 is a side elevational view of the ski harness shown in Fig. 4.

Fig. 6 is a plan view of a ski harness embodying another form of the invention.

Fig. 7 is a transverse vertical sectional view taken on line 7—7 of Fig. 6.

Fig. 8 is a fragmentary plan view of a ski harness embodying a still further development of the invention.

In the form of the invention illustrated in Figs. 1 to 3, inclusive, my improved ski harness comprises a base plate 10 secured by screws 11 and 12 to the upper surface of a ski 13 which has a transversely extending recess 14 formed in its upper side immediately rearwardly of the rear edge of the plate 10. A pair of toe clamp elements 15 are pivotally attached at their forward ends to the plate 10 by screws 16 which are adapted to be selectively positioned in any of a plurality of apertures 17 formed in the forward portion of the plate 10. The rear end portions of the elements 15 are provided with hooks 18 for connection with opposite extremities of a tension spring 19 by which the free end portions of the clamp elements 15 are yieldably, resiliently urged toward each other.

Formed on the outer edge portion of the elements 15 are upstanding flanges 20 which converge forwardly sufficiently to conform to the taper of the front or toe end portion of a shoe. Mounted on each of the flanges 20 is an inwardly projecting member 21 which is located immediately above the upper side of the shoe sole 22, shown in Fig. 1, and which is adapted to extend into the welt portion of the shoe in order to obstruct upward displacement of the toe portion of the shoe from the ski harness.

The inwardly projecting members 21 are detachably and adjustably mounted on the respective upstanding flanges 20 by a lug 23 and threaded stem 24 which may be selectively inserted in pairs of apertures 25 formed in the flanges 20 as shown in Fig. 1. A nut 26 on the threaded stem 24 detachably secures each inwardly projecting member 21 in place.

A shoe sole contacting and supporting plate 27 is disposed in superimposed relation above the clamping elements 15 and held, at its forward end, out of interfering engagement with these elements by spacers 28 through which screws 29

extend. The screws 29 are adapted to be threaded into selected apertures 30 formed in the base plate 10 in order to selectively position the plate 27 and abutment 31 formed in the forward extremity thereof. The abutment 31 comprises an upstanding flange which is adapted to engage and arrest forward movement of the front extremity of the sole portion 22 of the shoe. The rear end portion of the shoe sole contacting plate 27 has a downwardly offset marginal part 32 which is detachably secured to the ski 13 by screws 33. A plate 34 mounted on the upper side of the ski at a location rearwardly of the plate 27 serves to bring the heel 35 of the shoe to a desired elevation relative to that portion of the sole of the shoe which is held by the plate 27.

The shoe is urged forwardly against the abutment 31 and maintained in clamped engagement with the flanges 20 of the elements 15 by resilient means of conventional construction comprising a spring 36 which surrounds and fits into a groove formed in the heel 35. The forward end of this spring may be releasably tensioned by a toggle acting clamp, generally designated by the numeral 37, and which includes a lever 38 pivoted on a bracket 39 on the upper side of the ski 13, a connecting member 40 having a plurality of notches in which the forward end of the spring 36 is selectively engageable, and a link 41 by which the lever and connecting element 40 are operatively connected. Pivotal movement of the lever 38 in a counter-clockwise direction serves to tension the spring 36 for urging the shoe forwardly of the ski. The intermediate portion of the spring 36 may be held out of interfering relation with respect to the shoe and clamping mechanism by tongues 42 struck out of a plate 43, one of which is mounted on each side edge of the ski. This deflection of the spring 36 causes a downwardly directed force to be exerted on the shoe for yieldably urging the latter toward the ski.

In the operation of the ski harness shown in Figs. 1 to 3, the toe end portion of the ski shoe is yieldably held against lateral movement by the pivotal clamping elements 15 while the shoe is urged forwardly and the heel portion thereof urged downwardly by the spring 36, the abutment 31 arresting forward movement of the shoe. In the event the shoe is twisted in either direction in the plane of the upper surface of the ski, one of the clamping elements 15 is rotated outwardly about its pivot while the other element 15 is rotated inwardly about its axis by the spring 19 until arrested by abutment of the flange 20 against the edge portion 44 of the shoesole supporting plate 27 from which it is held in spaced relation by the sole 22 of the shoe while the latter is aligned with the ski. Since the shoe is held against forward movement by the abutment 31 which acts as a fulcrum, further twisting movement of the shoe after pivotal movement of one clamping element 15 has been arrested results in withdrawing of edge portions of the shoe on one side thereof from beneath the inwardly projecting member 21 of that side, thus permitting the shoe to become detached from the ski. The spring 19 thus retains the flanges 20 in clamping engagement with the sole 22 of the shoe while the latter is angularly displaced from alignment with the longitudinal axis of the ski a predetermined amount corresponding to the displacement by the shoe of the said one clamping element 15 from its innermost position plus an amount corresponding to the width of the inwardly projecting member 21 of that clamping element.

The amount the clamping elements are spread by the shoe may be varied for any one shoe by changing the position of the supporting plate 27. This action takes place when a skier falls, encounters an obstruction or is otherwise subjected to possible injury resulting from action which tends to twist his leg or legs. The amount of relative twisting movement of the shoe with respect to the ski required to release the shoe may be predetermined by selectively positioning the shoe sole supporting plate 27 longitudinally of the ski. The maximum force to which a skier's leg is subjected before the shoe is released from the ski may be predetermined by selecting a spring 19 of desired tensional strength. The position of the shoe with respect to the longitudinal axis of the ski may be selectively predetermined to suit the operator by selectively positioning the pivoted ends of the elements 15 at the location of the various apertures 17.

With the foregoing ski harness the skier may locate each shoe with respect to each ski in the foregoing manner to comply with his individual requirements and he may also limit the strain to which his legs will be subjected due to unintended twisting by the skier.

In the form of the invention illustrated in Figs. 4 and 5 the main portion of the ski harness is substantially identical to that shown in Figs. 1 and 3 and corresponding parts are designated by the same numerals. In this development of the invention the pivoted toe clamping elements 15 have converging edge portions 46 and rear extremities which bear against an adjustable abutment 47. The latter serves to arrest inward movement of the elements 15 due to twisting movement of the shoe of the nature above described. This abutment comprises a body portion 48 which is mounted to slide longitudinally of the ski under the action of a screw 49 having its forward end journaled in an aperture formed in a flange 50 extending upwardly from the portion 48. The screw 49 is threaded in a nut 51 rigidly secured to an upstanding flange 52 of a plate 53 which is mounted on the ski 13 by screws 54. The forward end of the screw 49 is held against withdrawal from the aperture of the flange 50 by a nut 55 which is pinned to the forward end of the screw. By adjusting the position of the abutment 47 longitudinally of the ski the extent to which the shoe may be twisted relative to the ski before its release therefrom may be selectively predetermined, the amount of such twisting movement corresponding to the angular displacement of the elements 15, by insertion of a shoe between the flanges 20, from their innermost positions as established by the setting of the abutment 47 plus an amount corresponding to the width of one of the inwardly projecting members 21.

The major portions of the ski harness shown in Figs. 6 and 7 are substantially identical to the structure shown in Figs. 1 to 3 and corresponding portions thereof are designated by the same numerals. In this form of the invention each toe clamp element 15 is provided with a rearwardly extending flange 56 having an aperture through which extends a threaded stud 57. Each stud 57 is supported at its inner end by a lug 58 extending rearwardly from the center portion of the rear edge of the base plate 10. A spring 59 mounted on each stud 57 bears between a flange 56 and a nut 60 adjustably threaded onto the outer extremity of the stud. The springs 59 yieldably urge the elements 15 inwardly toward each other with a

force which may be selectively predetermined by individual adjustment of the nuts 60. Inward movement of the elements 15 is arrested by engagement of the outer edge portion 61 thereof against the head of a screw 62 which is threaded into the base plate 10. The limiting inward positions of the elements 15 may be selectively predetermined by selecting a screw 62 having a head of suitable diameter. The amount of twisting movement of the shoe which may take place before it is released accordingly corresponds to the angular displacement of the elements 15, by insertion of a shoe between the flanges 20, from their innermost positions as established by the size of the head of the screw 62 plus an amount corresponding to the width of one of the inwardly projecting members 21. The forces with which the respective elements 15 are urged inwardly may be individually predetermined by independent adjustment of the nuts 60 and the maximum strain upon a skier's leg or legs by twisting of the ski in respectively opposite directions may be independently limited to conform to desired values.

The form of the invention illustrated in Fig. 8 is similar to that shown in Figs. 6 and 7 and corresponding parts are designated by identical numerals. In this form of the invention however a nut 63 is threaded on each stud 57 between the lug 58 by which the studs are supported and the respective flanges 56 of the elements 15. The nuts 63 serve as adjustable abutments for selectively and individually variably limiting inward pivotal movement of each toe clamping element 15 respectively. With this form of the invention the amount of relative twisting of the shoe with respect to the ski in opposite directions before detachment of the shoe from the ski occurs may be individually predetermined. The amount of twisting movement of the shoe which can take place before it is released accordingly corresponds to the angular displacement of the elements 15, by insertion of a shoe between the flanges 20, from their innermost positions as established by the positions of the nuts 63 plus an amount corresponding to the width of one of the inwardly projecting members 21. The force opposing outward pivotal movement of each element 15 may also be individually selectively predetermined.

Although but several embodiments of the invention are shown and described, it will be understood that various changes, including the size, shape and arrangement of parts, may be made without departing from the spirit of the invention and it is not my intention to limit the scope thereof other than by the terms of the appended claims.

What I claim is:

1. A harness for clamping a shoe to a ski and the like comprising an abutment securable to said ski for engagement with the toe extremity of said shoe, a pair of toe clamp elements each pivotally mounted on said ski at a location in advance of the part thereof which normally supports the shoe and adapted to extend along one side of the toe portion of said shoe respectively, said elements having inwardly projecting parts located rearwardly of the pivotal axes of said elements and engageable over forwardly converging opposite edge portions of the sole of said shoe, resilient means disposed rearwardly of said inwardly projecting parts yieldably urging said elements pivotally toward each other, said resilient means being adapted to retain said toe clamp elements in clamping engagement with said shoe throughout a predetermined range of angular movement of said shoe with respect to the longitudinal axis

of said ski and the projecting part of one of said elements being disengageable from the edge portion of said sole by relative separatory movement when said shoe is twisted while held against forward movement by said abutment substantially in the plane of said ski beyond said predetermined range of angular movement in order to accommodate separation of said ski and shoe prior to twisting of a skier's foot and leg to an injurious position, and means for urging said shoe forwardly into clamped engagement with said toe clamp.

2. A harness for clamping a shoe to a ski and the like comprising an abutment securable to said ski for engagement with the toe extremity of said shoe, a pair of toe clamp elements each pivotally mounted on said ski at a location in advance of the space thereon normally occupied by a shoe and adapted to extend along one side of the toe portion of said shoe respectively, said elements having inwardly projecting parts located rearwardly of the pivotal axes of said elements and engageable over opposite forward converging edge portions of the sole of said shoe, resilient means disposed rearwardly of and immediately adjacent said inwardly projecting parts yieldably urging said elements pivotally toward each other, said toe clamp elements being swingable with said shoe while in clamped engagement therewith for accommodating movement of said shoe relative to said ski throughout a predetermined range of angular movement, a stop for limiting pivotal movement of one of said elements during pivotal movement of said shoe beyond said predetermined range in order to accommodate disengagement of said protruding part of the latter element from the edge portion of said sole by relative separatory movement substantially in the plane of said ski and separation of said shoe from said ski when said shoe is twisted beyond said predetermined range of angular movement, and resilient means for urging said shoe into clamped engagement with said toe clamp.

3. A harness for attaching a shoe to a ski comprising a pair of toe clamp elements extending longitudinally of said ski, means for pivotally attaching the forward ends of said elements to said ski in advance of the position thereon normally occupied by said shoe, resilient means operating upon the rear end portions of said elements for yieldably urging the latter together, an inwardly projecting member on each of said elements located rearwardly of the pivotal axis thereof and adapted to engage over the edge portion of the sole of said shoe, a shoe sole support extending over said toe clamp elements having an abutment in advance of said members for arresting forward movement of said shoe relative to said inwardly projecting elements and a stop engageable with each of said elements for limiting inward movement thereof, and mechanism for urging said shoe forwardly against said abutment.

4. A harness for attaching a shoe to a ski comprising a pair of toe clamp elements extending longitudinally of said ski, means for pivotally attaching the forward ends of said elements to said ski in advance of the position thereon normally occupied by said shoe, resilient means operating upon the rear end portions of said elements for yieldably urging the latter together, an inwardly projecting member on each of said elements located rearwardly of the pivotal axis thereof and adapted to engage over the edge portion of the sole of said shoe, a shoe sole support extending over said toe clamp elements having an abutment

in advance of said members for arresting forward movement of said shoe relative to said inwardly projecting elements, an adjustable stop engageable with each of said elements for limiting inward movement thereof, means for shifting said stop and retaining the latter in a selected position, and mechanism for urging said shoe forwardly against said abutment.

5. A harness for attaching a shoe to a ski comprising a pair of toe clamp elements extending longitudinally of said ski, means for pivotally attaching the forward ends of said elements to said ski in advance of the position thereon normally occupied by said shoe, resilient means operating upon the rear end portions of said elements for yieldably urging the latter together, an inwardly projecting member on each of said elements located rearwardly of the pivotal axis thereof and adapted to engage over the edge portion of the sole of said shoe, a shoe sole support extending over said toe clamp elements having an abutment in advance of said members for arresting forward movement of said shoe relative to said inwardly projecting elements, a stop engageable with at

least one of said elements for limiting inward movement thereof, and mechanism for urging said shoe forwardly against said abutment.

6. A harness for attaching a shoe to a ski comprising a pair of toe clamp elements extending longitudinally of said ski, means for pivotally attaching the forward ends of said elements to said ski in advance of the position thereon normally occupied by said shoe, resilient means operating upon the rear end portions of said elements for yieldably urging the latter together, an inwardly projecting member on each of said elements located rearwardly of the pivotal axis thereof and adapted to engage over the edge portion of the sole of said shoe, a shoe sole support extending over said toe clamp elements having an abutment in advance of said members for arresting forward movement of said shoe relative to said inwardly projecting elements, a pair of independently adjustable stops one engageable with each of said elements, respectively, for limiting inward movement thereof, and mechanism for urging said shoe forwardly against said abutment.

DAVID A. WALLACE.
